ELECTROSTATIC MACHINE

Axel E. Landerholm, New York, N. Y.

Application April 13, 1937, Serial No. 136,761

10 Claims. (CL 171—329)

This invention relates to electrostatic machines for producing and storing up electrostatic charges for various uses and purposes.

A main object of the invention is to provide a simple and efficient and durable apparatus whereby electrostatic charges may be built up and stored by the use of a stream of gas.

A further object is to provide an apparatus wherein a charge collector is related inductively with a charge reservoir element and charges are moved from one and to another by the action of a circulating stream of gas.

A further object is to provide a simple apparatus whereby the main terminals may be adjusted with respect to each other without interfering with the circulating system.

A still further object is to provide a system in which the gas circulates in a substantially closed system so as to be used over and over again.

Generally speaking my invention comprises a pair of elements such as a charge distributing or collecting element such as a comb or set of needles or sharp points related inductively to a charge storage reservoir such as a hollow ball terminal, which are mechanically connected, in one example and as a preferred form only, by a system of passages wherein a gas flows so that the gas picks up the charge on one element and passes it to a reservoir or storage element. In one type of the system the gas when thus functioning is exhausted from the system when it has deposited its charge but in another type of my system the gas will flow continuously in the system and repeatedly pick up and deposit charges again and again and continue this cycle indefinitely.

It is well known that a sharp metal point on a charged conductor will cause the charge to rapidly disappear whether it be positive or negative and that charged air particles stream off the point in the form of the so-called "electric wind." It is equally true that if a needle point be held near to a charged conductor, the conductor will be discharged. For in this case the needle becomes oppositely charged by induction and electrifies the air which passes across and discharges the conductor.

A point is a region of extremely sharp curvature where an intense charge density obtains, and a consequent large potential gradient just off the tip. If the charge in question is positive, it will attract and snatch out of the immediate air some of the ever present free electrons floating there; and if the charge intensity is sufficient some of these will attain a velocity great enough

to knock electrons off neutral air molecules on the way—a process known as ionization by collision. The fresh electrons rush towards the needle in the same manner, and the positive heavy portions of the molecule repelled away, constituting the above mentioned "electrical wind." Ever present positive particles in the nearby air join in this streaming movement. This collision-ionization takes place in the thin layer of air in intimate contact with the needle points, the thin skin of air which adheres so close to the metal surface that it and the swift electronic processes taking place therein are but little disturbed by the comparatively sluggish air stream flowing by in the air passages. The repelled positive particles, however, are not confined to this thin layer but are urged away, aided by the attraction of the nearby sphere, toward which they are heading when the air current sweeps them away.

If the charge on the needles is negative, and the intensity sufficient, surface electrons will detach themselves and be driven off, together with near-by ever-present negative particles of air and dust; and these are swept away in the air passages.

A certain minimum potential must obtain before any appreciable discharge will take place from a needle point. For very sharp points, positively charged, discharges have been observed at 2500 volts. For similar points, negatively charged, minimum potential is several hundred volts lower. These potentials are low in electrostatic tension, and are readily available for "priming the machine." An ordinary electrophorus, for example, may have a potential of 50,000 volts.

More particularly the invention comprises a charge distributing or collecting element such as a comb or set of sharp points or teeth or needles which are disposed in inductive relation to a terminal such as a metallic hollow ball. The needles and the ball are directly associated with a series of passages or conduits through which a gas passes. This gas will flow past the needles and pick up a charge of one sign and then transfer it by continuous flow to a hollow terminal reservoir where it is stored up. In one form, the gas flows out of the system and in another form the gas is returned to the system to repeat the cycle.

Still more particularly the system comprises two charge collecting and distributing elements such as needles or combs inductively related respectively to a pair of hollow metallic ball terminals or storage elements. The collecting element of one pair of inductively related elements is connected by passages or conduits or closed passages

to the storage element or reservoir of the other pair of elements and similarly the collecting element of the other pair of inductively related elements is connected by passages or conduits with the storage element or terminal element of the first pair. A stream of gas such as air which may or may not be laden with a fine dust is then passed from element A in one pair of elements to element B' in the other pair of elements, and from element A' in the second pair of elements to element B in the first pair of elements. Thus the charges are gradually stored and built up on the storage elements which are adjustable at desired distances to regulate the discharge voltage and are so adjustable without in any way affecting the flow of the collecting and distributing stream of gas.

With these and other objects in view which will readily appear as the nature of the invention is better understood, the same consists in the improved construction and novel arrangement and combination of parts which will hereinafter be fully described and particularly pointed out in the appended claims.

In the accompanying drawings has been illustrated, a simple and preferred form of the invention, it being understood, however, that no limitation is necessarily made to the precise structural details therein shown but that alterations and modifications within the scope of the appended claims may be resorted to when desired.

In the drawings.

Fig. 1 is a side elevation of the apparatus with certain parts broken away;

Fig. 2 is a side elevation, enlarged, of one of the terminal units with some parts shown in section and other parts broken away;

Fig. 3 is an end elevation of the device shown in Fig. 2, with portions broken away and others in section;

Fig. 4 is a horizontal cross section through the device taken on the line 4-4 of Fig. 1;

Fig. 5 is a transverse vertical section through the line 5-5 of Fig. 2; and,

Fig. 6 is a schematic diagram of a modified form of the invention.

Referring to the drawings in detail wherein similar reference characters designate corresponding parts throughout the several views; 10 and 11 are elongated base blocks of insulating material with feet 12 of insulating material on block 10 and rollers 13 of similar material on block 11. Extending between the blocks 10 and 11 are three pipes 14, 15, and 16 which at one end are rigidly connected to short pipe extensions 17, 18, and 19 fastened to and extending into block 10. At their other ends the pipes 14, 15, and 16 are telescopically connected to pipes 20, 21, and 22 fastened to and extending into block 11 and being much longer than short pipes 17, 18, and 19 and permitting the blocks 10 and 11, while maintaining the pipe connections intact, to be adjusted at different distances from each other to control the gap between the terminal electrodes. The pipe 15 is at a lower level than the other two and has a T-connection therein with a valve 24 connected to an inlet pipe 25 to admit a desired current of air or other gas into the circulatory system at any desired pressure.

Rising from the blocks 10 and 11 are column supporting members having desired gas passages therein and corresponding parts of the supports rising from the block 11 are numbered the same as those on the column rising from the block 10

except for the primes attached thereto for convenience. These columns or supporting members are formed of a series of channelled plates such as 26, 27, 28, 29, and 30 connected together by means of rivets 31. Their conjunction affords air passages such as 32, 33, and 34, and a channel for a conductor 35. The pipe 18 connects to the bottom of the vertical air passage 33; the pipe 17 to a lateral extension passage 34a of the passage 34; the pipe 19 connects to a lateral extension passage 32a of the passage 32.

At the block 11 the pipe 20 connects to a lateral extension 32'a of a passage 32'; pipe 21 connects to 33'; and pipe 22 connects to lateral extension 34'a of passage 34'. At the top of the column 18 rising from block 10 is a head block or casing formed of sections 36 and 37 held together by screw bolts 38. The columns and the head blocks are made of insulating material also. The parts of the head block at the top of the column rising from block 11 are numbered the same as similar parts shown in Fig. 2 except for the primes. In section 36 is a passage 39 connecting at its lower end with passage 32 in the supporting column and at its upper end opening into the left end of a pipe 42, journalled near its middle at 43 in the section 37, and extending to the right beyond the section 37. On the outer end of the pipe 42 is a sleeve 44 supporting the metal screen 45 provided with a series of small holes 46 therein. The periphery of the screen supports the inter-threaded hemi-spheres 47 and 48 of a spherical metallic terminal ball which adjacent the head casing has an opening 49 spaced from the pipe 42 and curved inwardly as at 48.

The section 36 also has a vertical passage 40 which at its lower end connects with central passage 33 in the supporting column and at its upper end opens into a large chamber or reservoir 51 formed in the head casing by the abutment of the sections 36 and 37. The section 37 by reason of block 37' is provided with curved annular passage 52 which extends from chamber 51 around in a smooth curve and opens into an annular passage 41 in the section 37 which at its lower end connects with passage 34 in the supporting column. Embedded in the block 37' and extending therefrom into the passage 52 is a series of sharp points forming projecting portions 54 of a curved comb member 53. This comb member is connected to a wire or conductor 35 which extends downwardly through the channel formed between plates 28 and 29 and extends across the machine to connect to a similar comb in the opposite head casing. In this apparatus everything is of insulating material except the conductor 35, the combs 53 and 53', the sleeves 44 and 44', the screens 45 and 45', and the hemispherical terminal sections 47, 48, and 47', 48', although the rivets 31 and 31' and the screw bolts 38 and 38' may be made of metal or of insulating material.

In the drawings, the Fig. 6 is represented as a diagrammatic showing of a somewhat similar apparatus of modified form but involving a closed circulatory system with a pressure pump therein. In this modification there is shown a pair of spaced hollow spherical terminals 55 and 55' mounted on sleeves 56 and 56' which extend outwardly from hollow casings 57 and 57'. These casings are divided into two separate chambers by means of vertical partitions 58 and 58'. These chambers are numbered 59, 60, and 59', 60'. Conduits 61 and 61' are mounted on partitions 58 and 58' and extend within the sleeves 56 and 56' 75

and connect chambers 58 and 58' with the interior of the terminals 55 and 55'.

A pump 62 is operatively connected to pipes 63 and 64 and is adapted to force a gaseous medium such as air in the directions indicated by the arrows. At the right end, pipe 63 is connected to chamber 58' and at its left end it is connected to chamber 60. Pipe 64 at its right end is connected to chamber 60' and at its left end is connected to chamber 58. The flow of the gaseous elements through the system is therefore clearly shown by the arrows.

In the chambers 60 and 60' are disposed annular baffle rings 65, 65' supported on the inner walls of the chambers 60 and 60' and with their inner edges lying close to the sleeves 58, 58'. Between the rings 65, 65' and the adjacent terminals 55, 55' in chambers 60, 60' are disposed ring-like combs or series of needle like points 66, 66', disposed around the periphery of a metallic collar such as 67, 67' mounted on the sleeve 58, 58'. These comb elements are connected by a wire 68 preferably passing out of the chambers through the baffle ring 65, 65'. In the terminals 55, 55' are disposed a series of needles or comb teeth such as 69, 69', formed of metal points, and disposed adjacent the end of the pipe 61, 61'.

In considering the operation of the preferred forms of the invention, it will be apparent that in each and every form there is a current of gaseous medium flowing past a series of charge-carrying points disposed adjacent to a terminal bearing and storing a charge of an opposite sign and that means are provided for the gaseous medium to carry charges of suitable sign to that adjacent terminal.

In the form shown in Fig. 2, the air current admitted into the pipe 15 will travel up the middle passage 33 to the reservoir chamber 51 and then will pass across the comb teeth or needle points 54 bearing, for example, a negative charge, and pick up that charge and pass through the annular passages 52 to the larger circular passage 41, and thence to passage 34 in support column for casing sections 36 and 37 downwardly to pipe 14 through lateral passage 34a. It then traverses pipe 14 to lateral passage 32'a, thence to passage 32', up this passage to rear end of pipe 42' and through this pipe to the interior of the terminal sections 47, 48' wherein it gives up its charge to the walls of the terminal and passes out of the shell through the space between pipe 42' and curved portion 49' of the shell.

Similarly air passing from the inlet pipe 25 and passing to the right as in Fig. 4 will pass to vertical passage 33', to reservoir chamber 51', through annular passages 52', past comb teeth or needles 54', picking up a positive charge thereon and carrying it to circular passage 41', down passage 34' to lateral extension 34'a, through pipe 16 to lateral passage 32a to vertical passage 32 through pipe 42 into the interior of the hollow ball terminal element formed of hemi-spherical elements 47 and 48 and will deposit the charge thereon its speed of flow being retarded by the perforated screen 45 so as to permit time for the proper deposit of the charge before the gas passes out the opening adjacent curved portion 50 of the ball into the atmosphere. By adjusting the telescoping pipes connecting the base blocks 10 and 11 the distance between the adjacent surfaces of the balls may be regulated to determine the voltage at which there will occur a discharge therebetween.

In considering the form shown in Fig. 6, it is clear that this is a completely closed system as the gas is clearly shown as returning over and again the same path to repeat its cycle of picking up and depositing charges. Starting at the pump 62 at the bottom thereof the gas is forced to the left through pipe 64 carrying what is shown in this example as a positive charge and carries it through said pipe up to chamber 58 then through pipe 61 into interior of ball 55, 10 then the charge is deposited on the ball but the gas leaves the ball passing through sleeve 58 into chamber 63 past comb or sharp points 66 after passing baffle plates or rings 65 then down pipe 63 to the upper side of the pump then continues 15 along pipe 63 up through it to chamber 58' through pipe 61' into the interior of ball 55'. In this case the stream is carrying a negative charge picked up from the combs 66 which charge it deposits upon the interior of ball 55' then leaving the ball through sleeve 58' into chamber 63' past rings 65' past combs 66' down pipe 64 and back to the bottom of the pump thus completing one cycle of operation.

It is to be understood that when I use the word 25 stream herein I intend to cover a continuous single stream of gaseous material flowing through the system or a stream the parts of which, as herein illustrated in the preferred form of the invention, are divided at the inlet pipe and travel 30 in separate and distinct paths through the device.

I have therefore in these examples of the preferred form of the invention shown that a pair of elements are inductively related and that one is used as a sort of collector of charges from 35 which the charges are picked up by a stream of distributing gas and the other is used as a sort of storage element and that there may be two sets of these pairs of elements such that the charges are picked from an element of one pair 40 and carried to and deposited upon the other element of the other pair and vice versa.

While the invention has been described in detail and with respect to a present preferred form thereof, it is not to be limited to such details and 45 forms since many changes and modifications may be made in the invention without departing from the spirit and scope of the invention in its broadest aspects. Hence it is desired to cover any and all forms and modifications of the invention 50 which may come within the language or scope of any one or more of the appended claims.

What I claim is:

1. An electrostatic machine which comprises a charge collecting element and a charge storing element disposed in inductive relation, and means including gaseous streams flowing past said elements to remove a charge of given sign from the charge collecting element and to deposit a charge of opposite sign on the charge storing element.

2. An electrostatic machine which comprises a charge collecting element provided with sharp points inductively disposed relatively to a hollow ball charge storing terminal element, and means including gaseous streams flowing past said elements to remove a charge of given sign from said points and to deposit a charge of opposite sign upon the ball element.

3. An electrostatic machine which comprises two pairs of elements each pair comprising a 70 charge collecting element and a charge storing element disposed in inductive relation, and means including a gaseous stream flowing past said elements of each pair to remove a charge of given sign from one element of each pair and to

- deposit it upon the other element of each pair.
4. An electrostatic machine which comprises two pairs of elements each pair comprising a charge collecting element and a charge storing element disposed in inductive relation, and means including a gaseous stream flowing past all the elements to remove a charge of given sign from the collecting element of each pair and to deposit it upon the charge storing element of the other pair.
5. An electrostatic machine which comprises two pairs of elements each pair comprising a charge collecting element provided with sharp points inductively related to a hollow ball charge storing terminal element, and means including a gaseous stream flowing past all of said elements to remove a charge of given sign from one element of each pair and to deposit it upon the other element of the other pair.
6. An electrostatic machine which comprises two pairs of elements each pair comprising a charge collecting element provided with sharp points inductively disposed relatively to a hollow ball charge storing terminal element, and means including a gaseous stream flowing past said elements of each pair to remove a charge of given sign from the points of each pair and deposit it upon the ball element of the other pair.
7. An electrostatic machine which comprises a pair of elements each pair comprising a charge collecting element and a charge storing element disposed in inductive relation, a support for each pair of elements, adjustable connections between said supports, said supports and connections having passages therein for connecting said elements, and means including gaseous streams flowing in said passages past said elements of each pair, said passages disposed in such manner as to lead the gaseous streams progressively to and past the charge collecting element of one pair, thence to and past the charge storing element of the other pair, whereby the stream will remove a charge of given sign from one element in each pair and deposit it upon the other element of the other pair.
8. An electrostatic machine which comprises two pairs of elements each pair comprising a charge collecting element and a charge storing element disposed in inductive relation, a support for each pair of elements, adjustable connections between said supports, said supports and connections having passages therein for connecting said elements, and means including gaseous streams flowing in said passages past said elements of each pair, said passages disposed in such manner as to lead the gaseous streams progressively to and past the charge collecting element of one pair, thence to and past the charge storing element of the other pair, whereby the stream will remove a charge of given sign from the points of one pair and deposit it upon the ball element of the other pair.
9. An electrostatic machine which comprises two pairs of elements each pair comprising a charge collecting element provided with sharp points inductively disposed relatively to a hollow ball charge storing terminal element, a support for each pair of elements, adjustable connections between said supports, said supports and connections having passages therein for connecting said elements, and means including gaseous streams flowing in said passages past said elements of each pair, said passages disposed in such manner as to lead the gaseous streams progressively to and past the charge collecting element of one pair, thence to and past the charge storing element of the other pair, whereby the stream will remove a charge of given sign from the points of one pair and deposit it upon the ball element of the other pair.
10. An electrostatic machine which comprises two pairs of elements, each pair comprising a charge collecting element provided with sharp points inductively disposed relatively to a hollow ball charge storing terminal element, a support for each pair of elements, adjustable connections between said supports, said supports and connections having passages therein for connecting said elements, and means including gaseous streams flowing in said passages past said elements of each pair, said passages disposed in such manner as to lead the gaseous streams progressively to and past the charge collecting element of one pair, thence to and past the charge storing element of the other pair, whereby the stream will remove a charge of given sign from the points of one pair and deposit it upon the ball element of the other pair.

AXEL E. LANDERHOLM
